UNITED STATES PATENT OFFICE.

SMITH K. GERHARDT, OF EAST ST. LOUIS, ILLINOIS.

FOLDING CAR-STEP.

968,340.

Specification of Letters Patent. Patented Aug. 23, 1910.

Application filed May 27, 1910. Serial No. 563,691.

To all whom it may concern:

Be it known that I, SMITH K. GERHARDT, a citizen of the United States of America, residing in East St. Louis, county of St. 5 Clair, and State of Illinois, have invented certain new and useful Improvements in Folding Car-Steps, of which the following is a full, clear, and exact description, reference being had to the accompanying drawings, forming part of this description.

My invention relates to a folding car step for railway cars, and has for its object the production of an auxiliary step of this character controlled by strong and positive 15 operating devices which very firmly hold the step in its folded and unfolded positions.

Another object is to produce a folding step adapted to be controlled and operated by a trap door which normally closes the 20 upper end of the stepway in a car platform.

Figure I is a perspective view illustrating my invention. Fig. II is a perspective view of a portion of a hinge which connects the folding step sections. Fig. III is a detail 25 perspective view of the means for connecting the trap door to the step controlling mechanism. Fig. IV is a side elevation of the parts shown in Fig. I. Fig. V is a side elevation illustrating a modification. Fig. 30 VI is a horizontal section of the latch for holding the mechanism shown in Fig. V in either of its two positions.

In the accompanying drawings: A designates a car platform provided with a well 35 known type of trap door B adapted to cover the stepway leading from said platform.

5 is a latch pivoted to the end wall of the car for the purpose of locking the trap door B in its open position. When closed, the door may be locked by a catch 6 having a bolt 7 adapted to engage a plate 8 on the 40 top face of the door.

C designates a folding step composed of sections 1 and 2 connected together by a 45 hinge 3, the section 2 being hinged to the lower step of the stepcase at 4.

The means for causing the trap door B and the folding step to operate in unison comprises an arm 9 secured to a rock shaft 50 10 rotatably supported in the top riser of the stepcase, the arm 9 having projections 11 at its upper end which slide in a guide 12 secured to the under side of the trap door that causes the arm 9 to move in an arc of a 55 circle and rotate said rock shaft. Opening

and closing the trap door will, obviously, cause the upper end of the arm 9 to slide in the guide 12 and thus rock the shaft 10. A short lever arm 13 secured to the shaft 10 is pivoted to a rod 14 surrounded by a spring 15, said rod having a head 16 engaging one end of the spring. The other end of the spring 15 engages a spring seat on a bracket 17 secured to the stepcase and through which the rod 14 passes. While the door is being 65 closed, the shaft 10 and lever arm 13 are rocked so as to pull the rod 14 and place the spring 15 under compression. As this spring is compressed when the door is closed, it will cause the shaft 10 to rock slightly and thus 70 elevate the door to a certain extent whenever the door is released by the operation of the latch 6. The object of this door elevating device is to impart initial movement to the door and mechanism connected thereto, 75 and thus relieve the operator of the labor of starting these movements while the door is in a lowered position and lies flush with the floor.

A rock shaft 18 extending across the under 80 side of the stepcase has secured to it, at one of its ends, a lever arm 19 connected to a lever arm 20 on the end of the rock shaft 10 by a link 21. A pair of lever arms 22 carried by the rock shaft 18 are connected to 85 the outer edge of the folding step 1 by chains, or other flexible members, 23 passing through housings 24 on the bottom step of the main stepcase. The rock shaft 18 is also connected to the folding step 1 by a lever 90 arm 25 secured to said shaft and having its lower end pivoted to a link 26, the latter being pivotally connected to a bar 27 extending rearwardly from the folding step 1.

Assuming that the trap door B is open, as 95 shown in Fig. I, the folding step is then unfolded to form a continuation of the main stepcase and upon the closing of the trap door, the parts operate as follows: The upper end of the lever arm 9 will move downwardly due to connection with the trap door and rotate the rock shaft 10, with the result of causing the lever arm 20, link 21 and the lever arm 19 to move upwardly. This action imparts rotation to the rock shaft 18 100 and causes the lever arms 22 and 25 to move rearwardly to the position shown in full lines in Fig. IV. As the lever arms 22 move rearwardly, the chains 23 are pulled to fold the step sections 1 and 2, and at the same 110

time, the lever arm 25 is moved to pull these sections rearwardly and upwardly under the bottom step of the stepcase.

It will now be readily understood that opening the door will move the lever arms 22 and 25 to the position shown by dotted lines in Fig. IV, and during this movement, the chains 23 will be released to allow the folding step to unfold while the lever arm 25, through the medium of link 26 and the bar 27, pushes the step sections downwardly and outwardly.

When the folding step is in service, the chains 23 prevent the lower section 1 from moving down and it is prevented from moving inwardly by the immovably held parts connected to the bar 27, these parts being connected to the door B which is then locked in position by the latch 5, shown in Fig. I. Another means for holding the step section 1 in its proper position, when unfolded is the hinge 3, said hinge being composed of two sections, one of which has a lug 28 (see Fig. II) adapted to engage an abutment 29 on the other hinge section when the step is unfolded.

In the modified construction shown in Figs. V and VI, the mechanism for controlling the folding step is not operated by a door, the operating means therefor being adapted for use on cars not provided with a trap door covering the step. The lever arms 22' and 25' carried by the rock shaft 18' (shown in Fig. V) may be connected to the folding step in the same manner as the arms 22 and 25. The lever arm 19' for rocking the shaft 18' and thus operating the folding step, is normally held in the position shown by a spring 30. This spring 30 lies between a stationary spring seat 31 and a movable spring seat 32 on the end of a rod 33, the latter being pivoted to the lever arm 19'. 34 is a push rod pivotally connected to the lever arm 19' and having a projecting foot piece 34' at its upper end. The push rod 34 passes through a slot 36 in the end wall of the car and is adapted to be engaged by the foot of the operator to move the lever arm 19'. When the push rod 34 is elevated, it is locked in position by a spring pressed locking bolt 35, mounted in a housing 36 and having rack teeth 37 (see Fig. VI) which mesh with a sector 38 secured to a shaft 39. Before depressing the push rod 34, the operator must rock the shaft 39 to operate the sector, and thereby withdraw the locking bolt 35 from the aperture 40 in the locking bolt. After the push rod has been depressed to unfold the step, the spring pressed locking bolt 35 moves into an aperture 41 in said rod (see Fig. V) and thus locks all of the parts in position until the bolt is again withdrawn by the operation of the sector 38. This latter operation will cause the step to move automatically to its folded

position due to the energy stored in the spring 30 during the unfolding of the step.

I claim:

1. The combination with a stepcase of a folding step at the foot of said stepcase, a rock shaft rotatably supported by said stepcase, means for operating said rock shaft, means carried by said rock shaft having connection with said folding step for exerting a rear pull thereon when the step is to be folded and for supporting the step when it is unfolded, and means carried by said rock shaft and connected to said step whereby rearward movement of the step is prevented while it is unfolded. 80

2. The combination with a stepcase of a folding step at the foot of said stepcase, comprising a pair of sections hinged to each other, and one of which is hinged to said stepcase, a rock shaft rotatably supported by said step case, a pair of lever arms carried by said rock shaft, flexible connections between said lever arms and the lowermost of said step sections, and a third lever arm carried by said rock shaft and having link 90 connection with said lower step section. 85

3. The combination with a stepcase of a folding step at the foot of said stepcase, comprising a pair of sections hinged to each other, one of which is hinged to said stepcase, a rock shaft rotatably supported by said step case, a pair of lever arms carried by said rock shaft, flexible connections between said lever arms and the lowermost of said step sections, a third lever arm carried 100 by said rock shaft and having link connection with the lowermost step section, and a spring device for operating said rock shaft. 95

4. The combination with a stepcase of a folding step at the foot of said stepcase, comprising a pair of sections hinged to each other, one of which is hinged to said stepcase, a rock shaft rotatably supported by said stepcase, a pair of lever arms carried by said rock shaft, flexible connections between said lever arms and the lowermost of said step sections, a third lever arm carried 110 by said rock shaft and having link connections with the lowermost step section, and a spring device whereby said rock shaft is 115 operated to move said folding step to an unfolded position. 110

5. The combination with a stepcase of a folding step at the foot of said stepcase, comprising a pair of sections hinged to each other, one of which is hinged to said stepcase, a rock shaft rotatably supported by said stepcase, a pair of lever arms carried by said rock shaft, flexible connections between said lever arms and the lowermost of 120 said step sections, a third lever arm carried by said rock shaft and having link connection with the lowermost step section, a trap door at the top of said stepcase, and a spring device controlled by said trap door by which 125 130

said rock shaft may be actuated to move said folding step toward an unfolded position.

6. The combination with a stepcase of a folding step at the foot of said stepcase, comprising a pair of sections hinged to each other, one of which is hinged to said stepcase, a rock shaft rotatably supported by said stepcase, a pair of lever arms carried by said rock shaft, flexible connections between said lever arms and the lowermost of said step sections, a third lever arm carried by said rock shaft and having link connection with the lowermost step section, a trap door at the top of said stepcase, a second rock shaft supported by said stepcase, an arm carried by said second rock shaft and having engagement with said trap door, a spring for actuating said second rock shaft to partially open said trap door, and lever connection between said second rock shaft and said first named rock shaft actuated by said spring whereby said first named rock shaft is operated to move said folding step toward an unfolded position.

15 7. The combination with a stepcase of a folding step at the foot of said stepcase, comprising a pair of sections hinged to each

other, one of which is hinged to said stepcase, a rock shaft rotatably supported by said stepcase, a pair of lever arms carried by said rock shaft, flexible connections between said lever arms and the lowermost of said step sections, a third lever arm carried by said rock shaft and having link connection with the lowermost step section, a trap door at the top of said stepcase, a second rock shaft supported by said stepcase, an arm carried by said second rock shaft and 35 having engagement with said trap door, a spring for actuating said second rock shaft to partially open said trap door, and lever connection between said second rock shaft and said first named rock shaft actuated by 40 said spring whereby said first named rock shaft is operated to move said folding step toward an unfolded position.

SMITH K. GERHARDT.
